PORTABLE LIQUID DISPENSING STORAGE UNIT

Manuel C. Ray, 30407 Moonmist Drive,
Rancho Palos Verdes, Calif. 90274

Filed Nov. 1, 1974, Ser. No. 519,989

Term of patent 14 years

Int. Cl. D23—01

U.S. Cl. D23—2

FIG. 3

FIG. 1

FIG. 1 is a perspective view taken from the front, top and right side of a portable liquid dispensing storage unit showing my new design;

FIG. 2 is a front view thereof; and

FIG. 3 is a top view thereof.

I claim:

The ornamental design for a portable liquid dispensing storage unit, substantially as shown.
